UNITED STATES PATENT OFFICE.

CHARLES S. STAFFORD, OF SAN FRANCISCO, CALIFORNIA, ASSIGNOR OF
ONE-HALF TO JOHN H. BLAKEWAY, OF SAME PLACE.

RATCHET-DRILL.

SPECIFICATION forming part of Letters Patent No. 634,594, dated October 10, 1899.

Application filed April 18, 1899. Serial No. 713,493. (No model.)

To all whom it may concern:

Be it known that I, CHARLES S. STAFFORD, a citizen of the United States, residing in the city and county of San Francisco, State of California, have invented an Improvement in Ratchet-Drills; and I hereby declare the following to be a full, clear, and exact description of the same.

My invention relates to improvements in that class of drills which are actuated by a reciprocating lever and pawl-and-ratchet mechanisms known as "ratchet-drills."

It consists, essentially, in the combination of mechanism whereby a partial turn of the drill is effected by each forward and backward movement of the lever.

It also comprises means for reversing the movement of the drill and details of construction, which will be more fully explained by reference to the accompanying drawings, in which—

Figure 1 is a vertical section through the drill. Fig. 2 is a top view of the same. Fig. 3 is a top view of the intermediate gearing and showing three bevel-pinions. Fig. 4 is a view of the stationary structure of the drill. Fig. 5 is a view of the feed. Fig. 6 is an external view of the drill, the ratchet-wheels being shown incased.

A is a hollow cylinder head or casing from one side of which the handle A' projects. Within this casing is an annular ring or carrier B, about which the casing is loosely turnable, and a web extends from the peripheral part of the annular ring to the center, where it unites with and is supported by the central hollow sleeve B', through which the shank of the feed-screw and drill-carrier C pass. The web has a plurality of open channels formed in it, as shown at B'', and within these channels are journaled the beveled pinions D, of which there may be two, as shown in Figs. 1 and 2, or three, as shown in Fig. 3, the shafts of which are radially disposed between the outer ring and the central sleeve. Two or more of these pinions may be thus journaled to properly balance and act upon the gears E and F, one of which is formed with or fixedly united to a ratchet-wheel E' and the other is correspondingly fixed to or formed with a ratchet-wheel F'. These gears

engage the bevel-pinion upon opposite sides of their axes. One of these gears and ratchets is turnable upon the central hollow sleeve or spindle B' at one side of the web and pinions and the other upon the other side, so that the teeth of both gears E and F engage with the teeth of the pinions, and while one rotates in one direction by reason of this engagement the other will rotate in the opposite direction.

The drill fits into the socket at the lower end of the feed and carrier spindle C, and this screw-spindle is turnable in an exterior socket-piece G, screw-threaded, so that the drill may be advanced as the cut progresses by simply turning the two with relation to each other so as to advance the drill and its carrier. The upper end of the socket G contacts with the end of a stationary yoke H, being turnable with relation thereto, and this end of the socket-piece G is either made conical to fit a correspondingly-shaped depression in the yoke or it may have a head with grooves in its face and in the corresponding face of the yoke to form a raceway for balls, which thus allow the socket-piece to be turned freely when desired. The yoke has its ends fixed to a disk H', which surrounds the sleeve B' and is fixed thereto, so that the yoke, the disk, the sleeve with the web, and the outer ring B form a stationary structure within and about which the other parts are movable.

The object of the construction here shown is to advance the drill with each forward and backward movement of the lever, and to effect this I have shown pawls I and I', pivoted upon opposite sides of the part A, so that the end of one of the pawls engages the ratchet F and the other the ratchet F'. These pawls are normally held in position by means of springs J, which engage and return them to their normal position when they have been temporarily moved to one side by the turning of the ratchets. Stops K are fixed upon turnable pins L, which are journaled on the casing A in such relation to the pawls that one side of one of the pawls contacts with one of the stops to prevent its moving in that direction, thus temporarily holding the ratchet-wheel with which it engages, while the other side of the opposite pawl correspondingly

contacts with its stop to prevent its ratchet-wheel from turning in the opposite direction. One of the ratchet-wheels is thus free to turn in one direction and the other in the other by 5 the opposite reciprocations of the handle. A keyway is cut in the screw-spindle C and a corresponding key or feather f projects from the interior of the ratchet F', so that the turning of this ratchet will turn the spindle and 10 the drill. The pinions D, being engaged by the gear which is fixed to this ratchet-wheel, will be acted upon through the ratchet E' and its gear-wheel by the turning of the handle, and through this connection the spindle C 15 will also be turned, carrying with it the drill. The operation will then be as follows: The drill being set up at any point where work is to be done, the upper face of the yoke H being prevented from turning by projecting 20 pins or other corrugations, it is pressed against any suitably-disposed support, and the point of the drill resting against the surface which is to be perforated a movement of the handle A' in one direction will cause one of the pawls 25 I or I' to be pressed against the stop K and temporarily prevented from turning. By the first movement of the lever-arm in one direction it is now assumed that the pawl which engages the ratchet F' contacts with its stop, 30 so that the ratchet cannot turn with relation to the handle. It is therefore moved in unison with the handle and will thus advance the spindle C and the drill a distance equal to the distance to which the handle is turned. 35 When the handle is brought back in the opposite direction, the pawl I, which engages the ratchet-wheel E' upon the opposite side, will contact with its stop K, and the return movement of the handle will cause this pawl 40 to turn the ratchet E' in unison with the return movement of the handle. This movement, acting through its gear-wheel, turns the pinions D, and these pinions act upon the gear which is connected with the ratchet 45 F' to turn it in the opposite direction, and as this presses its pawl I' away from the stop the spring which holds the pawl will yield and allow the pawl to pass over the teeth of the ratchet while this portion of the 50 movement takes place, so that the drill will be advanced in the same direction by this return movement of the lever that it was by the previous movement in the opposite direction. The action of the pawls and ratchets 55 is alternate, one being held by its stop while the handle is being moved in one direction, while the other moved over the teeth of its ratchet to allow of this motion and the reverse action taking place when the handle is 60 returned, while the forward movement of the drill-spindle and drill is effected at each movement of the lever.

If it is desired to reverse the movement of the drill and to back it out, it is done by 65 turning the stems which carry the stops K a half-revolution. This removes the stop K from one side of the pawl I and turns a simi-

lar stop to contact with the opposite pawl, while the turning of the other stem and stop performs a like office for the other pawl and 70 ratchet.

Whenever the spindle C and the socket-piece G are allowed to turn freely, they will move in unison when the handle A' is moved and no feed will take place; but whenever the socket-piece G is retarded or held stationary then the spindle C, having screw-threads which are turnable in the socket-piece, will be advanced, and thus advance the drill through the hollow sleeve B' as long as 80 the socket-piece G is prevented from turning. This may be effected by taking hold of a disk G², which is fixed to the socket-piece, or preferably by means of a brake or frictional plate G³, which is adapted to contact with one side 85 of the socket-piece G and is moved by means of a thumb-screw passing through a collar N, fixed to the yoke, said thumb-screw having a milled head G⁴ projecting through the side of the yoke in a convenient position to be operated by the user of the tool. Thus under normal conditions the screw will be turned back, so that the brake G³ will not press upon the socket-piece and the latter will turn with the drill without advancing the latter. By 95 turning the screw by its milled head the brake may be pressed against the socket-piece, so as to retard it or stop it, as the case may be, and the screw-spindle C will then turn independently and will advance the drill as much 100 as may be desired. The drill may be retracted, as previously stated, by the reversal of the stops which engage the two parts, or it may be retracted directly without its turning by turning the socket-piece by hand, so 105 that it will withdraw the screw-threaded spindle and the drill without the latter turning.

Having thus described my invention, what I claim as new, and desire to secure by Letters Patent, is—

1. In a drill, a hollow head with a handle by which it may be turned, a stationary ring fitting within said head having a central sleeve through which the drill-spindle and socket-piece pass, beveled pinions journaled 115 radially within the stationary ring, ratchets having beveled gears attached to them and engaging the pinions upon opposite sides, one of said ratchets having a key or feather which engages a corresponding keyway in the 120 drill-spindle, pawls pivoted upon the head or handle engaging the ratchets and stops against which the opposite sides of the pawls contact to alternately prevent one ratchet from turning while the other is allowed to 125 move freely.

2. In a drill, a threaded spindle by which the drill is carried, a socket-piece in which the threaded spindle is turnable, a fixed yoke against which the outer end of the socket-piece contacts and is turnable, a central sleeve through which the socket-piece passes, said sleeve being rigid with the fixed yoke and having a web and outer peripheral ring, a 130

corresponding hollow circular head which is turnable about said ring and a lever by which it is moved, pinions radially journaled in the web, beveled gears carried by the ring and 5 ratchets which engage opposite sides of the pinions, spring-pressed pawls engaging said ratchets and stops carried upon the head and so disposed with relation to the pawls that one of said pawls engages its ratchet to advance it when the lever is moved in one direction and is released to allow the ratchet to turn freely when the handle is moved in the other direction while the opposite pawl is engaged and released by its stop in alternation therewith.

3. In a ratchet-drill, a spindle carrying the drill at one end and being threaded and turnable within a socket-piece, a fixed yoke against which the opposite end of the socket- 20 piece contacts and is turnable, a sleeve rigid with the yoke and having radially-journaled beveled pinions turnable within a hollow head from which the actuating-lever projects, ratchets engaging the pinions upon opposite 25 sides whereby the ratchets and gears will be turned in opposite directions, a keyway and feather by which the drill-spindle engages and is turnable with one of the ratchets while advancing with relation thereto, spring- 30 pressed pawls mounted upon the turning head engaging the ratchets and reversible stops against which opposite sides of the pawls contact whereby each ratchet is alternately allowed to turn in one direction and prevented 35 from turning in the other direction or the movement thereof reversed.

4. In a drill of the character described, a drill-carrying feed-spindle, a socket-piece in which the spindle is turnable, a yoke and a sleeve rigid therewith, through which the 40 socket-piece passes, and a ring rigid with the sleeve, the actuating-ratchets, the pinions mounted in the fixed ring and sleeve and disposed between the ratchets, a lever and pawls for operating the ratchets, a brake-shoe, and 45 an actuating-screw carried by the fixed yoke and adapted to contact with and retard or stop the rotation of the socket-piece whereby the rate of advance of the drill is regulated.

5. In a ratchet-drill of the character described, the double ratchets, gears, a stationary yoke and a sleeve and ring rigid therewith, said sleeve and ring having said gears mounted between them, a head turnable about said ring and pinions and a lever by 50 which it is moved, and pawls carried upon the head and engaging the ratchets whereby the latter are alternately advanced to turn the drill with each reciprocation of the lever, the feed-screw spindle and socket-piece in 55 which it is turnable, said socket-piece having the ball-bearing disk and raceway at its head and a corresponding raceway in the yoke and balls fitted in said raceway, substantially as described.

In witness whereof I have hereunto set my hand.

CHARLES S. STAFFORD.
